[57] CLAIM

The ornamental design for a lavatory faucet set, sub-
stantially as shown and described.

DESCRIPTION

FIG. 1 is a perspective view of a lavatory faucet set
showing my new design;

FIG. 2 is a front elevational view thereof; and

FIG. 3 is a right side elevational view thereof, the left
side being a mirror image of the right side shown.

FIG. 2

FIG. 3
